CLAIM

The ornamental design for a container closure, as shown and described.

DESCRIPTION

FIG. 1 is a perspective view of of a container closure, showing my new design;

FIG. 2 is a top view of the section of the container closure of FIG. 1;;

FIG. 3 is a front view of the container closure of FIGS. 1 and 2;

FIG. 4 is a rear view of the container closure of FIGS. 1-3; and,

FIG. 5 is a side view of the container closure of FIGS. 1-3.

The broken lines depict environmental subject matter only, and form no part of the claimed design. In addition, the portions of the container arrangement that are not shown in the drawing do not form any part of the claimed design.
